ROTARY HYDRAULIC PUMP

Clarence J. Coberly, Los Angeles, Calif., assignor,
by mesne assignments, to Dresser Equipment
Company, Cleveland, Ohio, a corporation of
Ohio

Application December 20, 1948, Serial No. 66,158

25 Claims. (Cl. 103—44)

1

My invention relates to fluid-operated pumps and, more particularly, to a rotary type of such pump.

The present invention is of particular utility when used as a well pump in the oil industry and, consequently, will be described in connection with such use, but it is to be understood that I do not desire or intend to be limited thereto.

Conventional fluid-operated well pumps used in the oil industry include a fluid-operated motor having a reciprocating motor piston therein and a single or double acting pump piston mechanically connected to the motor piston, operating fluid under high pressure being supplied to the motor piston by a suitable main valve so as to reciprocate the motor piston. The main valve of such a pump is either hydraulically or mechanically reciprocated in direct response to reciprocation of the pistons.

A primary object of the present invention is to provide a novel fluid-operated pump having a rotatable rotor unit containing one or more reciprocating pistons, the rotation of the rotor-actuating valve means to control the flow of fluid to and from the pistons. I prefer to accomplish this by utilizing the rotor as a rotatable valve member for controlling the flow of fluid, and this is a further object of the invention.

Another object of the invention is to provide such a novel fluid-operated pump which includes such a rotor and which is capable of pumping against high pressures.

Still another object of the invention is to provide such a fluid-operated pump which employs a stationary cam plate for converting reciprocating motion of the pistons into rotary motion of the rotor.

A further object of the invention is to provide such a fluid-operated pump in which the cam plate is used to rotate the rotor carrying the pistons, power applied to the motor piston area being transmitted directly to the pump piston area during the working stroke without using the cam plate for the transmission of such power. I also prefer to utilize the cam plate to cause the return stroke of the pistons, which is another object of my invention.

Another object of the invention is to provide such a novel pump having a plurality of pistons carried by the rotor, each of the pistons being rotated upon its own axis during rotation of the rotor so as to reduce sliding friction of the pistons in their cylinders and to equalize wear thereon.

Another object of the invention is to provide such a novel pump in which the rotor co-operates

with a stationary valve plate to control the flow of fluid to and from the pistons.

A still further object of the invention is to provide such a novel pump in which the pumping stroke of the pump piston area is caused by applying operating fluid under pressure to the motor piston area and in which return stroke of the pistons is produced by the rotation of the rotor relative to the cam plate.

Another object is to provide such a pump in which the operating fluid lubricates the relatively moving parts thereof.

A further object of the invention is to provide such a pump with a rotary valve which operates in timed relation to the position of the rotor and pistons to control the intake and discharge of both the motor and the pump.

Another object is to provide such a pump including a rotor and a valve plate in which a hydraulic balance is provided therebetween to eliminate or control end thrust of the rotor against the valve plate.

Still another object of the invention is to provide such a pump having a combined valve for the motor intake and discharge and the pump intake and discharge, in which a differential fluid pressure on the pump piston times the effective pump port area is equal and opposite to a differential fluid pressure on the motor piston times the effective motor port area.

Another object of the present invention is to provide a fluid-operated pump of the character hereinbefore described which may be used either alone or in multiple to obtain the desired pumping capacity.

Another object is to provide such a pumping device including a plurality of fluid-operated pump units of the character hereinbefore set forth and having separate inlets for conveying fluid to be pumped to the inlet ports of the respective units.

Another object in connection with one embodiment of the invention is to provide such a pumping device having an outlet for the spent operating fluid and pumped fluid which is common to all of the fluid-operated units.

Still another object is to provide a pumping device in which two or more fluid-operated pump units of the invention are connected in tandem and in which operating fluid for the motor of each succeeding unit in the series passes through the preceding unit in the series.

Another object is to provide a piston plunger having a major area continuously exposed to pump discharge pressure, a minor area alter-

nately exposed to pump intake pressure and to pump discharge pressure, and an annular area alternately exposed to operating fluid pressure and to pump discharge pressure.

The foregoing objects and advantages of the invention, together with various other objects and advantages thereof which will become apparent, may be attained through the employment of the exemplary embodiments of the invention which are illustrated in the accompanying drawings and which are described in detail herein-after. Referring to the drawings:

Fig. 1 is a diagrammatic utility view showing a fluid-operated pumping device embodying the invention as installed in a well;

Fig. 2 is an enlarged longitudinal sectional view of the upper end of the invention;

Fig. 3 is a longitudinal sectional view of an intermediate portion of the invention and is a downward extension of Fig. 2;

Fig. 4 is a longitudinal sectional view of the lower end of the invention and is a downward extension of Fig. 3;

Figs. 5, 6, 7 and 8 are transverse sectional views respectively taken along the broken lines 5—5, 6—6, 7—7 and 8—8 of Fig. 3;

Fig. 9 is a longitudinal sectional view which is similar to Fig. 3 but which illustrates the upper end of another embodiment of the invention;

Fig. 10 is a longitudinal sectional view of the embodiment illustrated in Fig. 9 and is a downward extension of Fig. 9; and

Figs. 11 to 15 are transverse sectional views respectively taken along the broken lines 11—11 to 15—15 of Fig. 9.

Referring particularly to Fig. 1 of the drawings, I show a casing 30 set in a well and extending into an oil-producing formation 31 of the well, the casing being perforated, as indicated at 32, to admit oil and other fluids, such as gas, water and the like, into the casing from the oil-producing formation. Extending into the well casing 30 and supported by a casing head 33 are power and production tubings 34 and 35, the latter being connected at their lower ends by a fitting 36. Connected to the lower end of the fitting 36 is a tubular receiver 37 for a fluid-operated pump 38 of the invention, the receiver being aligned with and, in effect, forming an extension of the tubing 34 in the particular construction illustrated. Connected to the lower end of the receiver 37 is a fitting 39 through which fluid is admitted from a body 40 of fluid in the well casing 30.

Considering the general operation of the apparatus as thus far described, an operating fluid, such as clean crude oil, is delivered under pressure to the pump 38 through the power tubing 34 to operate the pump as will be described in more detail hereinafter. The well fluid entering the receiver 37 through the fitting 39 is discharged into the production tubing 35 by the pump 38 and flows upwardly through the production tubing to the surface. Operating fluid may be delivered to the power tubing 34 by any suitable apparatus (not shown) as is well known in the art.

In the particular application of my invention illustrated in the drawings, the power and production tubings 34 and 35 are arranged side by side and the pump 38 is of the so-called free type so that it may be pumped into and out of the well as is well known in the art and as will be discussed in more detail hereinafter. Any suitable valve control apparatus for controlling the flow of power oil to pump the pump 38 into and

out of the well may be employed. For example, such a control apparatus may comprise a fluid-operated pump head such as that disclosed in my Patent No. 2,338,903, issued January 11, 1944.

It will be understood that the present invention is not to be regarded as limited to application to an apparatus such as that hereinbefore described since it is susceptible of various other applications as will be apparent to those skilled in the art. For example, the invention is not limited to application to a free pump such as the pump 38 and may be embodied in a fixed pump for well pumping purposes if desired. Also, the invention is not limited to the particular tubing arrangement shown.

Considering in more detail the illustrative embodiment of the invention which is illustrated in Fig. 1 of the drawings, the fitting 36 connecting the lower ends of the power and production tubings 34 and 35 to the pump receiver 37 is, as best shown in Fig. 3 of the drawings, provided with a bore 41 therethrough into which the power tubing and the tubular receiver are threaded, the power tubing being threaded into the upper end of the bore 41 and the receiver being threaded into the lower end thereof. Disposed in the bore 41 is a liner 42 having an internal diameter slightly less than the internal diameters of the power tubing 34 and the tubular receiver 37. The lower end of the production tubing 35 is threaded into a bore 43 in the fitting 36 and communicating with the bore 43 is a lateral passage 44 which terminates in an annular groove 45 formed in the fitting 36 and encircling the line 42, the latter having a plurality of radial openings 46 therein which communicate with the annular groove 45 and which perform a function to be discussed hereinafter.

Referring now to Fig. 4 of the drawings, the inlet fitting 39 is threaded on the lower end of the tubular receiver 37 and is provided with an annular, internal shoulder which supports a collar 47, the latter providing a tapered seat for an externally tapered pump seat member 48. The member 48 provides a tapered seat 49 for the fluid-operated pump 38. Threaded onto the lower end of the pump seat member 48 is an inlet fitting 50 which carries a check valve 51 for preventing outflow. Connecting the lower end of the bore 43 in the fitting 36 with a bore 52 in the fitting 39 is a tube 53, the bore 52 being connected to a space 54 below the pump 38 by a port 52a so that this space is exposed to fluid pressure in the production tubing 35 for a reason to be discussed hereinafter.

Referring to Figs. 3 and 4, the fluid-operated pump 38 includes an upper pump unit 55 and a lower pump unit 56 disposed in tandem. The two pump units 55 and 56 are of similar construction so that only the upper pump unit 55 will be described in detail. The pump unit 55 includes a cam fitting 57 at its upper end, a valve fitting 58 at its lower end, connected together in spaced relation by a tubular shell 59, and a cylinder barrel or rotor 60 rotatably mounted upon a tubular shaft 61.

The cam fitting 57 is disposed in the liner 42 opposite the radial openings 46 therein when the pump is in its operating position in the tubular receiver 37. The cam fitting 57 makes a sliding fit with the liner 42 and carries means for providing fluid-tight seals on either side of the radial openings 46 in the liner, the sealing means being exemplified as a pair of O-rings. The cam fitting 57 is provided at its lower end

with a portion of reduced diameter onto which the tubular shell 59 is threaded, this shell providing a chamber 62 from which the cylinder barrel 60 is spaced to provide an annular space 63 therebetween. The lower end of the tubular shell 59 is threaded onto the upper end of the valve fitting 58. Threaded into the upper end of the cam fitting 57 is a pressure inlet member 64 having an axial bore 65 and provided with radial ports 66 which communicate with the interior of the power tubing 34. Threaded into the inlet member 64 and extending upwardly therefrom is a two-piece stem 67 having resilient expandable packing cups 68 thereon, as shown in Fig. 2.

As shown in Fig. 3, the cam fitting 57 is provided with an axial bore 69 which communicates at its upper end with the bore 65 and at its lower end with a counterbore 70. Also provided in the cam fitting 57 is a longitudinal discharge passage 71 which communicates at its upper end through a radial port 72 with an annular groove 73 which registers with the radial liner openings 46. The discharge passage 71 communicates at its lower end through a radial port 74 with the upper end of the chamber 62. The lower end of the cam fitting 57 is provided with a plane cam face 75 which is disposed at an angle to the axis of the cam fitting.

The cylinder barrel 60 rests upon a valve 77 provided at the upper end of the valve fitting 58, the barrel being rotatably mounted on the tubular shaft 61. The tubular shaft 61 is provided, adjacent its upper end, with an annular shoulder 78 which rests upon the upper end of the barrel 60 to prevent longitudinal movement of the tubular shaft. The tubular shaft is also provided with suitable packing, such as O-rings, adjacent its upper and lower ends so as to form a seal between the exterior of the shaft and the cam fitting 57 and the valve fitting 58, respectively. As best shown in Fig. 5, the cylinder barrel 60 is provided with a plurality of circumferentially spaced cylinder bores 79 and, although four of such bores are shown in the embodiment illustrated, it is to be understood that more or less may be employed as desired. Provided in the lower portions of each of such bores 79 is a tubular liner 80, the major portion of which is spaced from the wall of the bore to provide an annular space 81 therebetween. The lower end of each of the liners 80 is provided with a longitudinal inlet passage 83, which, as best shown in Fig. 6, is preferably arcuate in form. The periphery of each of the liners 80 is also provided with a longitudinal pressure inlet groove 84 which communicates at its upper end with the annular space 81.

Disposed in each of the cylinder bores 79 is a piston plunger 85, the upper portion 86 of which makes a close-sliding fit in the bore 79, the lower portion 87 being of reduced diameter and making a close-sliding fit in the tubular liner 80, the two portions being separated by an annular shoulder 88 forming a high-pressure area. The upper end of each of the plungers 85 is provided with a bevelled follower face 90 which engages the cam face 75 of the cam fitting 57. As will be understood, the upper ends of the plungers 85 extend into the chamber 62, forming pumping portions of the plungers.

The valve fitting 58 is provided with an axial bore 92 which communicates at its upper end with an annular groove 93 and a counterbore 94 into which the lower end of the tubular shaft

61 extends. Formed in the valve fitting 58 and communicating with the annular groove 93 is a plurality of inlet passages 95, all of which communicate at their upper ends with a supply recess 96 formed in the valve face 77. Also formed in the valve fitting 58 is a plurality of well fluid inlet passages 98 which communicate at their upper ends with an arcuate inlet recess 99 formed in the valve face 77. The lower ends of each of the well fluid inlet passages 98 communicate through the corresponding radial port 100 with an annular space 101 provided between the receiver 37 and the tubular shell 59 and valve fitting 58. Also provided in the valve fitting 58 is a plurality of longitudinal discharge passages 102 which communicate at their upper ends, as shown in Fig. 7, with an arcuate discharge recess 103, and communicate at their lower ends, as shown in Fig. 4, through individual radial ports 104 with the exterior of the valve fitting 58. The lower end of the valve fitting 58 is provided with a plane cam face 105 which is identical with the cam face 75 of the cam fitting 57.

As shown in Fig. 4, and as indicated above, the lower pump unit 56 is substantially identical with the upper pump unit 55, including a cylindrical barrel 107, a lower barrel fitting 108, and a tubular shell 109 connecting the lower valve fitting with the valve fitting 58. Connected to the lower end of the lower valve fitting 108 is a pump inlet member 110, the lower end of the bore 111 of the lower valve fitting 108 being closed by a plug 112 disposed between the lower valve fitting and the pump inlet member. The pump inlet member 110 is provided with an axial inlet bore 114 and a plurality of radial passages 115 connecting the bore with a space 101 around the exterior of the fluid-operated pump 38. The lower end of the pump inlet member 110 is provided with a seating space 116 adapted to seat on and form a fluid-tight seal with the tapered seat 49. Suitable packing 117 is provided on the periphery of the pump inlet member 110 so as to form a fluid-tight seal between the pump inlet member and a liner collar 118 welded or otherwise secured in the lower end of the receiver 37. As will be noted, the liner collar 118 serves to space the fluid-operated pump 38 from the receiver 37.

In operation, high-pressure operating fluid, such as clean crude oil, is conveyed downwardly through the power tubing 34 past the packing cups 68 and through the radial ports of the pressure inlet member 64 into the fluid-operated pump 38. Such operating fluid flows downwardly through the axial bores 65 and 69 and through the tubular shaft 61 to the annular groove 93 in the valve fitting 58.

In the upper pump unit 55, with the parts in the position shown in Fig. 3, the left-hand piston plunger 85 is moving downwardly and has almost reached the bottom of its downward stroke, and the right-hand piston plunger 85 is moving upwardly and has almost reached the top of its upward stroke. In this position, operating fluid flows from the annular groove 93 up through the pressure inlet passages 95 to the supply recess 96, and thence upwardly through the longitudinal pressure inlet groove 84 communicating with the supply recess, and through the annular space 81 to the shoulder 88 on the right-hand piston plunger 85. Such application of operating fluid to the annular shoulder 88 of the right-hand piston plunger 85 causes it to continue its upward stroke until its follower face

90 passes over the highest point on the cam face 75. As the right-hand piston plunger 85 moves upwardly, its upper portion 86 occupies an increasingly greater volume in the chamber 62 thus displacing fluid therefrom upwardly through the radial port 74, the longitudinal discharge passage 71, the radial ports 72, the radial openings 46, the annular groove 45, the lateral passage 44, and into the bore 43 of the fitting 36, whence it flows upwardly through the production tubing 35 to the surface of the ground. It will thus be appreciated that the upstroke of each of the plungers 85 constitutes the pumping stroke thereof, being caused by the application of operating fluid under relatively high pressure to the pressure area provided by the annular shoulder 88.

During the upstroke, or pumping stroke, of the right-hand piston plunger 85, as seen in Fig. 3, the lower end thereof performs a suction stroke. Thus, as the piston plunger moves upwardly it draws well fluid through the check valve 51, upwardly through the inlet bore 114 and through the radial passage 115 into the annular space 101 through which it flows upwardly and through the radial ports 100, flowing up through the inlet passages 90, the arcuate recess 99, and the inlet passage 63 into the tubular liner below the piston plunger.

Upward movement of the right-hand piston plunger 85, as seen in Fig. 3, in engagement with the cam face 75 exerts a rotational force upon the cylinder barrel 60, causing it to rotate on the tubular shaft 61. As the right-hand piston plunger 85 passes the highest point on the cam face 75, rotation of the cylinder barrel 60 moves the pressure inlet groove 84 of that piston plunger out of registry with the supply recess 96 in the valve face 77, thus shutting off the flow of operating fluid to that piston plunger. Continued rotation of the cylinder barrel 60 then causes such pressure inlet groove 84 of that piston plunger 85 to register with the discharge recess 103, and spent operating fluid can then flow from below the shoulder 88 of that piston plunger through the annular space 81, the inlet groove 84, the discharge recess 103 and one of the radial ports 104 into the annular space 63 and to the chamber 62. At the same time that the inlet groove 84 registers with the discharge recess 103, the inlet passage 83 also registers with the discharge recess to permit displacement if well fluid from below the piston plunger 85. Continued rotation of the barrel 60 causes the piston plunger 85 to move downwardly on its return stroke from the highest to the lowest point on the cam face 75, the angle of the cam face and the rotation of the barrel causing such return stroke. As will be noted, the fluid in the chamber 62 is always at substantially the same fluid pressure as exists in the production tubing 35, and, as during the downstroke of the piston plunger 85, the annular shoulder 88 and its lower end are both in fluid communication with the chamber 62, during the downstroke of the piston plunger the hydraulic pressures thereon are substantially balanced. During the down or return stroke of the piston plunger 85, spent operating fluid is expelled by the annular shoulder 88 through the annular space 81 and the inlet groove 84 into the discharge recess 103 and thence through the annular space 63 into the chamber 62. At the same time, well fluid is expelled from below the piston plunger 85 through the inlet passage 83 into the discharge recess 103 where it mingles with the spent

operating fluid, and thence through the space 63 into the chamber 62. The down or return stroke of the piston plunger 85 thus requires only enough power to overcome friction between the piston plunger and the cam face 75, and between the piston plunger and its cylinder bore 73, and the fluid friction required to displace the spent operating fluid and well fluid therebelow into the chamber 62, and, since the piston plunger is substantially hydraulically balanced, it requires only little power to perform its return stroke. No pumping action occurs on the downstroke of the piston plunger 85, the spent operating fluid and well fluid therebelow merely being displaced into the chamber 62.

After the right-hand piston plunger 85, as seen in Fig. 2, passes the highest point on the cam face 75, it, of course, exerts no further turning moment on the cylinder barrel 60, continued rotation of the barrel being caused by the upstroke of one of the other plungers 85 moving from the lowest point to the highest point on the cam face, the piston plungers operating sequentially to maintain rotation of the barrel.

As the right-hand piston plunger 85 moves to the lowest point on the cam face 75, rotation of the barrel 60 causes its inlet passage 83 and its inlet groove 84 to move out of registry with the discharge recess 103 and again with registry with the recesses 99 and 96, respectively, to commence another cycle of operation of that piston plunger. All of the piston plungers 85, of course, operate in identically the same manner but sequentially. Each piston plunger 85 on its upstroke, or pumping stroke, displaces a volume of fluid from the chamber 62 upwardly through the production tubing 35. Upon its downstroke, the spent operating fluid and well fluid below the piston plunger 85 are displaced into the chamber 62, the volume of such displaced operating and well fluid being equal to the volume of fluid displaced from the chamber 62 on the pumping stroke. With four or more piston plungers 85, the discharge into the production tubing 35 is at a substantially constant rate. Although I have, for convenience of illustration, shown only four piston plungers 85, in practice I prefer to use five or seven thereof so as to smooth out the operation of the device.

It is to be noted that as the cylinder barrel 60 rotates upon its axis, each of the piston plungers 85 also rotates upon its own axis, due to engagement of its cam follower face 90 with the cam face 75, and this is an important feature of the invention as it reduces friction and equalizes wear on the piston plungers. It is also to be noted that in this invention each of the piston plungers 85 serves as both a pump and engine on its upstroke, the application of power being directly from the engine to the pump portions of the plunger and no pumping power being transmitted on the upstroke through the cam face 75, and this is a further important feature of the invention. In fact, the only function of the cam face 75 is to rotate the cylinder barrel 60 to control the valve means of the pump unit and to cause the return stroke of each piston plunger.

It will also be understood that by the construction described I provide a combined valve mechanism for the engine intake and discharge controlling the flow of operating fluid to and from the pressure area provided by shoulder 88, and for the pump intake and discharge. The recesses 96, 99 and 103 are so proportioned as to

area and leakage therebetween as to eliminate end thrust on the cylinder barrel 60 tending to separate it from the valve face 77 or in the opposite direction so as to increase the rotational friction therebetween, the hydraulic pressures on the cylinder barrel being substantially balanced. Hydraulic balancing of the cylinder barrel 60 may be attained by making equal the net upward and downward forces applied thereto, the net downward force being equal to the difference between the discharge column pressure and the well pressure times the effective area of the pump inlet recess 99, and the net upward force being equal to the difference between the operating fluid pressure and the discharge column pressure times the effective area of the engine supply recess 96. Due to the fact that some fluid will flow from the recess 96 to the recess 99, the effective areas of these recesses are somewhat greater than the actual areas thereof.

The operation of the lower pump unit 56 is identical with that of the upper pump unit 55, as described above, and need not be described in detail. Operating fluid flows to the lower pump unit 56 through its tubular shaft similar to the shaft 61, and spent operating fluid and well fluid therefrom flow upwardly through the longitudinal discharge passages 102 into the discharge recess 103 of the valve fitting 58, where they mingle with the flow from the upper pump unit 55. The pump units 55 and 56 are thus in tandem and operate simultaneously. It will also be noted that the lower valve fitting 108 of the lower pump unit 56 is identical with the valve fitting 58 of the upper pump unit 55, thus permitting an additional pump unit (not shown) to be connected in tandem below the lower pump unit 56. Although two pump units 55 and 56 are shown connected in tandem, it will be apparent that one or more of such pump units may be employed as required, to provide a desired total pumping capacity for the fluid-operated pump 38.

An alternative embodiment of the invention is shown in Figs. 9 to 15 of the drawings, including a fluid-operated pump 130 which is generally similar to the previously described fluid-operated pump 38, the pump 130 being shown operatively positioned in a tubular receiver 37a. The fluid-operated pump 130 includes only a single pump unit for convenience of illustration so that, in the present embodiment, the tubular receiver 37a is correspondingly shorter. However, in all other respects, the tubular receiver 37a and the parts connected thereto are identical to the corresponding parts of the previously described embodiment and are identified by the same numerals with the suffix "a" added thereto. As will be understood, although I have elected to show the fluid-operated pump 130 as including but a single pump unit, any number of such pump units may be connected in tandem as hereinbefore discussed.

The fluid-operated pump 130 includes a fitting 57a having a tubular shell 59a threaded onto the lower end thereof to provide a chamber 62a, and threaded onto the lower end of the shell is a valve fitting 58a. The valve fitting 58a is generally similar to the valve fitting 58 of the previous embodiment, the lower surface of which is adapted to serve as a cam for another pump unit (not shown).

Threaded onto the lower end of the valve fitting 58a is a pump inlet member 110a for the pump 130, which is adapted to engage the tapered

seat 49a provided by the pump seat member 48a in the fitting 39a. The valve fitting 58a is provided with an axial bore therethrough which is closed at its lower end by the plug 112a on the pump inlet member 110a.

Extending axially of the chamber 62a is a tubular shaft 61a, the ends of this shaft being disposed in the counterbores 10a and 94a and being suitably sealed with respect to the fitting 57a and being splined or otherwise locked with respect to the fitting 58a. The interior of the tubular shaft 61a communicates with the power tubing 34a through the axial bore 69a in the fitting 57a, the axial bore 65a in the pressure inlet member 64a and the radial openings 72a therein.

Rotatably mounted on the tubular shaft 61a is a cylinder barrel 60a, the barrel having a plurality of cylinder bores 79a therein which are open at their upper ends. Reciprocable in and projecting from the upper ends of the cylinder bores 79a are piston plungers 85a. Each piston plunger 85a is provided at its upper end with a cam follower face 90a which is complementary to the cam face 75a. Each piston plunger 85a is also provided with an annular shoulder 88a.

As best shown in Figs. 9 and 11, the external surface of the tubular shaft 61a is provided with a semi-annular intake groove 131 which is connected to the interior of the tubular shaft by a radial port 132. The cylinder barrel 60a is provided with a plurality of radial motor ports 133 which communicate with the lower ends of the respective cylinder bores 79a and which are adapted to register in sequence with the intake groove 131 to admit operating fluid under pressure sequentially into the cylinder bores. As in the case of the previously described embodiment, the intake groove 131 is of such length and is so positioned with respect to the cam face 75a that operating fluid under pressure is admitted into the cylinder bore 79a during the interval that the cam follower faces 90a on the corresponding piston plungers 85a are in engagement with the rise of the cam face 75a.

Diametrically opposite the intake groove 131 in the external surface of the tubular shaft 61a is an exhaust groove 134 with which the motor ports 133 are adapted to register in sequence to discharge spent operating fluid from the cylinder bores 79a during the downstroke of the piston plungers 85a. The exhaust groove 134 communicates with the chamber 62a by way of a longitudinal groove 135 in the external surface of the tubular shaft 61a. Thus, the tubular shaft 61a and the cylinder barrel 60a serve as a valve means for controlling intake and exhaust of operating fluid into and from the cylinder bores 79a, each cylinder bore receiving a charge of operating fluid under pressure during the upstroke of the corresponding piston plunger 85a, and such charge of operating fluid after it is spent being discharged therefrom during the downstroke of the corresponding piston plunger.

As best shown in Figs. 9 and 14, the upper end 65 of the valve fitting 58a is provided with an arcuate inlet recess 99a which is adapted to receive well fluid to be pumped from the annular space 101a within the tubular receiver 37a through radial inlet passages 100a and longitudinal inlet passages 98a. The lower ends of the cylinder bores 79a are adapted to register with the arcuate inlet recess 99a in sequence during rotation of the cylinder barrel 60a to admit well fluid to be pumped into the lower ends of the cylinder bores. As in the previously described embodiment, the

arcuate inlet recess 99a is so located that the cylinder bores 79a register therewith during the upstroke of the corresponding piston plungers 85a.

Also formed in the top of the valve fitting 58a is an arcuate outlet recess 103a with which the lower ends of the cylinder bores 79a are adapted to register in sequence to permit the discharge of pumped well fluid from the bores. The outlet recess 103a is so positioned with respect to the cam face 75a that the lower ends of the cylinder bores 79a register therewith during the down-stroke of the corresponding piston plungers 85a.

In the particular construction under consideration, the outlet recess 103a communicates with the chamber 62a surrounding the cylinder barrel 60a through radial ports 104a so that the pumped well fluid and the spent operating fluid are mixed in the chamber 62a and flow therefrom into the production tubing 35a through the previously described connecting passages. It will be understood, however, that if mixing of the pumped well fluid and expended operating fluid is not desired, the outlet recess 103a may be connected to a separate tubing (not shown).

Referring to Figs. 9 and 11, the interface between the tubular shaft 61a and the cylinder barrel 60a is lubricated by operating fluid through a radial port 136 and a groove 137 in the external surface of the tubular shaft. If desired, the interface between the tubular shaft 61a and the cylinder barrel 60a may be lubricated at a plurality of axially spaced points in this manner. Lubrication of the piston plungers 85a is accomplished by providing connected longitudinal and transverse passages 138 and 139, respectively, in the piston plungers, each longitudinal passage 138 communicating with the chamber 62a surrounding the cylinder barrel 60a so that fluid may flow from the chamber through the longitudinal and transverse passages to lubricate the piston plungers.

The operation of the fluid-operated pump 130 is similar to that of the fluid-operated pump 38 and it is thought that a further description of the operation of the pump 130 is unnecessary.

The cylinder barrel 60a is substantially hydraulically balanced in the axial direction by admitting operating fluid into an annular recess 141 in the top of the valve fitting 58a around the tubular shaft 61a, the operating fluid being admitted into this recess by way of the splined connection between the valve fitting and the tubular shaft. The annular recess 141 is of such a size that the operating fluid therein applies an upward force to the barrel 60a substantially equal to the difference between the downward force applied thereto by the fluid mixture in the chamber 62a and the upward forces applied thereto by the fluid in the recesses 99a and 103a.

It will be noted that the aforementioned axial forces applied to the cylinder barrel 60a are not coaxial, so that a turning moment tending to displace the barrel about an axis normal to its axis of rotation is applied thereto. Also, the operating fluid in the groove 131 applies a lateral force to the cylinder barrel which is only partially compensated by the fluid in the diametrically opposite exhaust groove 134. These conditions are compensated for by the operating fluid in the groove 137.

Although I have disclosed a specific application of my invention herein and have disclosed exemplary embodiments thereof for purposes of illustration, it will be understood that I do not intend to be limited specifically thereto since the

invention is susceptible of various other applications and since various changes, modifications and substitutions may be incorporated in the particular embodiments disclosed, all without necessarily departing from the spirit of the invention as set forth in the appended claims.

I claim as my invention:

1. In a fluid-operated pump, the combination of: a chamber; cam means in said chamber; cylinder means providing at least two cylinders each having an end communicating with said chamber and facing said cam means; piston means in each of said cylinders and extending into said chamber into engagement with said cam means, said piston means being movable into said chamber to displace fluid therefrom, the interaction between said cam means and said piston means upon movement of said piston means into said chamber producing relative rotation between said cam means and said cylinder means; means for admitting fluid to be pumped into said chamber; and means for alternately connecting the other end of each of said cylinders to a source of operating fluid under pressure and to said chamber.

2. In a fluid-operated pump, the combination of: a chamber; cam means in said chamber; cylinder means providing at least two cylinders each having an end communicating with said chamber and facing said cam means; piston means in each of said cylinders and extending into said chamber into engagement with said cam means, said piston means being movable into said chamber to displace fluid therefrom, the interaction between said cam means and said piston means upon movement of said piston means into said chamber producing relative rotation between said cam means and said cylinder means; means, including valve means responsive to relative rotation between said cam means and said cylinder means, for admitting fluid to be pumped into said chamber; and valve means responsive to relative rotation between said cam means and said cylinder means for alternately connecting the other end of each of said cylinders to a source of operating fluid under pressure and to said chamber.

3. In a fluid-operated pump, the combination of: a chamber; stationary cam means in said chamber; a rotor provided with at least two cylinders each having an end communicating with said chamber and facing said cam means; piston means in each of said cylinders and extending into said chamber into engagement with said cam means, said piston means being movable into said chamber to displace fluid therefrom, the interaction between said cam means and said piston means upon movement of said piston means into said chamber producing rotation of said rotor relative to said cam means; means for admitting fluid to be pumped into said chamber; and valve means for alternately connecting the other end of each of said cylinders to a source of operating fluid under pressure and to said chamber.

4. In a fluid-operated pump, the combination of: a chamber; stationary cam means in said chamber; a rotor provided with at least two cylinders each having an end communicating with said chamber and facing said cam means; piston means in each of said cylinders and extending into said chamber into engagement with said cam means, said piston means being movable into said chamber to displace fluid therefrom, the interaction between said cam means and said

piston means upon movement of said piston means into said chamber producing rotation of said rotor relative to said cam means; means, including valve means responsive to rotation of said rotor, for admitting fluid to be pumped into said chamber; and valve means responsive to rotation of said rotor for alternately connecting the other end of each of said cylinders to a source of operating fluid under pressure and to said chamber.

5. In a fluid-operated pump, the combination of: a chamber; a rotor; at least two reciprocable piston means carried by said rotor and movable into said chamber to displace fluid therefrom, said piston means having pressure areas thereon which, when exposed to fluid pressure, cause movement of said piston means into said chamber; means for rotating said rotor; means for moving said piston means out of said chamber; and valve means responsive to rotation of said 15 rotor for alternately connecting each of said pressure areas to a source of operating fluid under pressure and to said chamber.

6. A fluid-operated pump according to claim 3 including means for rotating each of said piston means about its own axis in response to rotation of said rotor.

7. In a fluid-operated pump, the combination of: a chamber; cam means in said chamber; a rotor; at least two reciprocable plungers carried by said rotor and each having a pumping end extending into said chamber and adapted to engage said cam means, each of said plungers having an intermediate high-pressure area thereon; means for admitting fluid to be pumped to said chamber; and means for alternately connecting each of said high-pressure areas to a source of operating fluid under pressure and to said chamber, the operating fluid under pressure acting on each of said high-pressure areas moving the corresponding plunger toward said cam means to displace fluid from said chamber, the interaction of said cam means and said plungers producing rotation of said rotor and said cam means producing the return strokes of said 30 plungers.

8. A fluid-operated pump according to claim 7, including means for hydraulically balancing the fluid pressures on each of said plungers during its return stroke.

9. In a fluid-operated pump, the combination of: a chamber; cam means in said chamber; a rotor having at least two plunger cylinders therein each providing a major bore and a minor bore, said minor bores being adapted to communicate with a source of fluid to be pumped; a reciprocable plunger in each of said cylinders having a major portion in said major bore of such cylinder and a minor portion in said minor bore thereof, said major portion of each plunger extending into said chamber into engagement with said cam means, the junction of said major and minor portions of each plunger defining a high-pressure motor area and the minor portion of each plunger defining a suction area; and valve means responsive to rotation of said rotor for alternately connecting each motor area and suction area first to said chamber and then to a source of operating fluid under pressure and a source of fluid to be pumped, respectively, each of said plungers moving toward said cam means when said motor area thereof is connected to a source of operating fluid under pressure so as to displace fluid from said chamber, movement of said plungers toward said cam means causing 35

rotation of said rotor to actuate said valve means, said cam means producing return movement of said plungers.

10. A pump, including: a chamber; at least two cylinders each communicating at one end with said chamber; pistons in said cylinders, respectively, each of said pistons being movable into said chamber to displace fluid therefrom; valve means for alternately connecting the other end 10 of each of said cylinders to a source of fluid to be pumped and to said chamber; and means for reciprocating said pistons in said cylinders.

11. A pump according to claim 10 wherein said cylinders are formed in a rotor and wherein each of said pistons is provided with a high-pressure area, said pump including: cam means in said chamber and engageable by said pistons, the interaction between said pistons and said cam means producing rotation of said rotor; and valve means for alternately connecting said high-pressure areas to a source of operating fluid under pressure and to said chamber.

12. A fluid-operated pump, including: a stationary cam having a cam surface; a stationary valve member provided with an intake port, an exhaust port, and an inlet port therein; a rotor between said cam surface and said valve member, said rotor being rotatable relative to said cam and said valve member about an axis which intersects said cam and said valve member, said rotor being provided with a plurality of spaced cylinders which are spaced from and parallel to said axis, said rotor being provided with a plurality of operating fluid ports which respectively communicate with said cylinders and which are adapted to register with said intake and exhaust ports in sequence during rotation of said rotor, and being provided with a plurality of pumped fluid ports which respectively communicate with said cylinders and which are adapted to register with said intake and exhaust ports in sequence during rotation of said rotor; and a plurality of pistons respectively reciprocable in said cylinders, each of said pistons having at one end thereof a cam follower which is adapted to engage said cam surface and having at the opposite end thereof two transverse pressure surfaces respectively exposed to fluid pressures obtaining in the corresponding operating fluid and pumped fluid ports, said cam followers being adapted to cooperate with said cam surface to convert linear movement of said pistons under the influence of operating fluid pressure applied thereto through said operating fluid ports into rotational movement of said rotor, whereby to move said operating fluid ports in said rotor into registry with said intake and exhaust ports in said valve member in sequence and to move said pumped fluid ports in said rotor into registry with said inlet and exhaust ports in said valve member in sequence.

13. A fluid-operated pump as set forth in claim 12 wherein said rotor is provided with a transverse end surface in contact with said valve member, and wherein said operating fluid and pumped fluid ports extend through said end surface of said rotor.

14. A fluid-operated pump according to claim 13 wherein said rotor is carried by a tubular shaft which communicates with and is adapted to convey operating fluid under pressure to said intake port in said valve member.

15. In a fluid-operated motor, the combination of: a tubular shaft adapted to receive operating fluid under pressure for operating said motor; a stationary cam having a cam surface which en-

circles said shaft; a rotor rotatable about said shaft adjacent said cam surface and provided with a plurality of spaced cylinders which are spaced from and parallel to said shaft; a plurality of pistons respectively reciprocable in said cylinders, each of said pistons having at one end thereof a cam follower which is adapted to engage said cam surface and having at the opposite end thereof a transverse pressure surface exposed to fluid pressure in its cylinder; intake valve means for admitting operating fluid under pressure from the interior of said shaft into said motor cylinders in sequence; and exhaust valve means for discharging fluid from said motor cylinders in sequence.

16. In a fluid-operated pump, the combination of: means providing a plurality of cylinders; a piston in each of said cylinders and providing first and second transverse surfaces facing one end thereof; intake valve means for admitting fluid under pressure to said first surfaces in sequence to move said pistons in one direction in their cylinders in sequence; means operatively connecting said pistons for moving said pistons in the opposite direction in their cylinders in sequence; and inlet valve means for admitting a fluid to be pumped to said second surfaces in sequence, said inlet valve means operating concurrently with said intake valve means.

17. In a fluid-operated pump, the combination of: a rotor providing a plurality of cylinders generally parallel to the axis of rotation of said rotor; a piston in each of said cylinders and providing first and second transverse pressure surfaces facing one end thereof; intake valve means operable in response to rotation of said rotor for admitting an operating fluid under pressure to said first pressure surfaces in sequence to move said pistons in one direction in their cylinders in sequence; and means operatively connecting said pistons for moving said pistons in the opposite direction in their cylinders in sequence, and for rotating said rotor in response to movement of said pistons in said one direction in their cylinders.

18. A fluid-operated pump as defined in claim 17 wherein the means last defined includes cam means engageable by said pistons.

19. A fluid-operated pump according to claim 17 including in addition: inlet valve means operating concurrently with said intake valve means and in response to rotation of said rotor for admitting a fluid to be pumped to said second pressure surfaces in sequence; and discharge valve means operating in response to rotation of said rotor for discharging fluid from said cylinders in sequence.

20. In a fluid-operated pump, the combination of: stationary cam means; a rotatable rotor provided with a cylinder which is spaced from and parallel to the axis of said rotor and which is provided with an open end facing said cam means; a piston reciprocable in said cylinder and projecting therefrom toward said cam surface, said piston being adapted to engage said cam means at one end and having at the opposite end thereof two transverse pressure surfaces within said cylinder; intake valve means for periodically admitting operating fluid under pressure to one of said transverse pressure surfaces; inlet valve means for periodically admitting fluid to be pumped to the other of said transverse pressure surfaces; and exhaust valve means for periodically discharging fluid from said cylinder.

21. In a fluid-operated pump, the combination

of: stationary cam means; a rotor rotatable about an axis intersecting said cam means and provided with a plurality of spaced cylinders which are spaced from and parallel to said axis; a plurality of pistons respectively reciprocable in said cylinders, said pistons being adapted to engage said cam means and each having first and second transverse pressure surfaces, said pistons being biasable toward said cam means by the action of an operating fluid under pressure on said first pressure surfaces thereof so as to bias said pistons into engagement with said cam means; intake valve means for admitting operating fluid under pressure to said first pressure surfaces in sequence; inlet valve means for admitting fluid to be pumped to said second pressure surfaces in sequence; and exhaust valve means for discharging fluid from said cylinders in sequence.

22. In a fluid-operated motor, the combination of: a chamber; cam means in said chamber; a rotatable rotor; said rotor having a plurality of longitudinal cylinders therein; a plurality of pistons respectively reciprocable in said cylinders, each of said pistons having one end thereof adapted to engage said cam means and having at the opposite end thereof a transverse pressure surface exposed to fluid pressure in its cylinder; intake valve means for admitting fluid under pressure for operating said pistons in said cylinders in sequence; and exhaust valve means for connecting said cylinders to said chamber in sequence so as to discharge fluid from said cylinders into said chamber in sequence.

23. In a fluid-operated pumping device, the combination of: a first fluid-operated motor and pump having a rotatable combined motor and pump unit, and first central passage means through the combined motor and pump unit of said first motor and pump for conveying operating fluid thereto; and a second fluid-operated motor and pump having a rotatable combined motor and pump unit, and a second central passage through the motor and pump unit of said second motor and pump communicating with said first passage and adapted to supply operating fluid to said second motor and pump, operating fluid conveyed to said second motor and pump passing through said first motor and pump.

24. In a rotary motor and pump unit adapted to be used in a fluid-operated pump, the combination of: a rotary pump barrel having a plurality of cylinder bores therein and circumferentially spaced about the axis of said barrel; a tubular shaft extending through said barrel and axially aligned therewith, said barrel being carried by said shaft; a piston plunger in each of said cylinders, each having an end extending therefrom and provided with a cam follower face; and means for connecting said cylinders in fluid communication with the interior of said tubular shaft.

25. In a fluid-operated pump, the combination of: an upper fitting having a cam face on the lower end thereof, and provided with a pressure port and a discharge port; a lower fitting having a valve face on the upper end thereof, and provided with a suction port; a tubular shell connecting said fittings in longitudinally spaced relation; a tubular shaft supported by said fittings and extending therebetween, the interior of said tubular shaft communicating with said pressure port and said valve face; a cylinder barrel rotatably mounted on said shaft within said shell, said barrel having a plurality of longitudinal cylinders therein, said barrel engaging said valve face and co-operating therewith to form valve means for

said ports; and a combined motor and pump piston in each of said cylinders and adapted to engage said cam face to rotate said barrel.
